UNITED STATES PATENT OFFICE.

FRANK J. MILLER, OF CLEVELAND, OHIO.

ENGINE.

No. 900,757.

Specification of Letters Patent.

Patented Oct. 13, 1908.

Application filed December 12, 1906. Serial No. 347,478.

To all whom it may concern.

Be it known that I, FRANK J. MILLER, citizen of the United States, residing at Cleveland, in the county of Cuyahoga and State of Ohio, have invented new and useful Improvements in Engines, of which the following is a specification.

This invention relates particularly to internal combustion engines.

10 The object of the invention is to provide suitable means for storing energy, in the form of compressed air, when the engine is working under less than full load, and for utilizing same to increase the power of the 15 engine when needed.

Another object is the novel application of the above means to a two-cylinder vertical four-cycle internal combustion engine of the type having both pistons connected to the 20 same throw of the crank-shaft.

In the drawings, Figure 1 is a vertical section of a two-cylinder four-cycle gas engine provided with my improvement. Fig. 2 is a vertical section on the line $x-x$ of Fig. 1. 25 Figs. 3 and 4 are details in section of the cam for operating the valves.

Referring specifically to the drawings, A are trunk pistons arranged to reciprocate in cylinders B and connected to cranks D by 30 connecting rods C. Cranks D are of the same throw and consequently the movement of the pistons A is the same.

E is a trunk piston arranged to reciprocate in cylinder F, and connected to crank H by 35 connecting rod G. Crank H is of opposite throw to cranks D and consequently the movement of piston E is opposite to the movement of pistons A. Cylinder F is located between cylinders B, consequently 40 crank H is between cranks D. Cylinder F has inlet and outlet puppet valves I and J in the head thereof.

O is a cam shaft which is driven from the crank shaft by intermeshing gearing at one- 45 half the rotary speed of the crank shaft. Cam P on the cam shaft engages with the rollers Q and R on the ends of a bell crank S which is connected to a rocker arm U by rod T.

50 The cam P has four positions, and is made with a sliding fit on cam shaft O and its key, and is shifted by yoke V and rod W. The cam P through line 1-1 is concentric with shaft O and consequently is in idle position

for the valve operating mechanism. When 55 the cam P is in the idle position, piston E draws in air through valve I during the down stroke, then valve I is closed by spring M, and during the up-stroke of piston E said air or part thereof is forced through valve J 60 and pipe K into an air reservoir L. Valve J is closed by spring N.

When the pressure in the air reservoir L is as high as desired, cam P is shifted to position 2. The cam P through line 2-2, as 65 shown, has two low places cut directly opposite each other into which roller R is pressed by coiled spring X on rod T, which at the same time raises rod T, and through rocker arm U opens valve I during the up- 70 stroke or part thereof, of piston E, thereby allowing the air which is drawn through valve I to be exhausted through the same valve I.

The cam P through line 2-2 may also be 75 made concentric with shaft O, its diameter to be equal to the distance across the cam at the two low points above referred to, which would allow spring X to hold valve I open continually.

The preferable proportion of the compression space in cylinder F is to be such that the pressure usually maintained in the air reservoir is nearly equal to the highest compression in the compression space, to 85 avoid trouble should the operator fail to shift cam P from position 1 to position 2, in which case piston E would continue to pump air into the reservoir until the pressure in the reservoir would be equal or nearly equal, 90 to the highest pressure in the compression space. When the pressure in the reservoir and the compression space are equal, or nearly equal, valves I and J will remain on their seats, and the air remaining in cylinder 95 F will be expanded and compressed. The only loss in efficiency will be due to friction of the moving parts.

When it is desired to increase the power of the engine by utilizing the stored energy in 100 the form of compressed air, cam P is shifted to position 3. The cam P through line 3-3, as shown, has two high parts directly opposite each other and low places cut at 90° from said high parts. It will be understood 105 from the drawing that when a high part of cam P engages with roller R, roller Q, through bell crank S, is forced into a low

place of said cam, at the same time, through rod T and rocker arm U, opening valve J and allowing compressed air from reservoir L to enter cylinder F during the down stroke, or part thereof, of piston E.

As above explained, cam P is driven at one-half the rotary speed of the crank shaft, consequently when piston E has completed its down stroke the crank shaft has rotated 10 one-half turn and the cam shaft O has rotated one-fourth turn bringing said high part of cam P in position to engage roller Q, which through rod T and rocker arm U opens valve I during the up stroke, or part 15 thereof, of piston E, allowing the expanded air to exhaust. It is to be understood that cam P, at position 3, is to be so designed in regard to the timing of valves I and J, that is, in regard to the lead and cut-off of said 20 valves, as to give best results with respect to economy and efficiency.

When it is desired to use said compressed air for starting the engine, cam P is shifted to position 4. The cam P, through line 25 4-4, is similar to said cam P through line 3-3, except that the cam P through line 4-4 is so designed as to open valve J during the entire down stroke and valve I during the entire up stroke.

30 It is to be understood that the approach to each position of cam P is tapered so as to enable the operator to shift the cam when the engine is at rest.

The air reservoir, as shown, is small in 35 proportion to the engine. It is to be understood that said reservoir may be made any suitable size or construction and the air pressure may be such as is found to be most practical. The advantage of having a large 40 air reservoir and maintaining a high compression is obvious.

As shown, the air reservoir has two compartments. The smaller compartment L' has a check valve l, so arranged as to allow 45 air to enter from reservoir L and to prevent said air from returning to reservoir L when the air in reservoir L' is being used. The compressed air in reservoir L' may be used for any desired purpose.

50 The advantage of having the pistons A connected to the same throw of the crank D is that by timing the valves and sparks accordingly, the explosions in the cylinders B will occur alternately and in equal succession, consequently there will be one working stroke to each revolution of the engine.

The advantage of having piston E connected to crank H of opposite throw to cranks D is that the working strokes of pis-

ton E will alternate with the working strokes 60 of pistons A.

The advantage of having cylinder F located between cylinders B is that during the working stroke of piston E and the compression stroke of one of the pistons A and exhaust stroke of the other piston A, or during the working stroke of one of the pistons A and the intake stroke of the other piston A, and the compression stroke of piston E, when the cranks D and the crank H are horizontal, or at 90° from the position shown in the drawings, the angle of the connecting rods C and the angle of the connecting rod G are opposite and the pressure on piston E and on one of the pistons A, while the connecting rods are at said opposite angles, causes a pressure on the side of cylinder F opposite to the pressure on the side of one of the cylinders B. It is obvious that the said 75 opposite pressures cannot be in the same plane and therefore will tend to cause vibration. It is also obvious that to minimize vibration the said opposite pressures should be as nearly in the same plane as possible. Therefore it is of particular advantage to 80 have cylinder F located between cylinders B.

I claim:

1. In an explosive engine, the combination of a compression cylinder having inlet and outlet valves in the head thereof, a reservoir 90 connected to the outlet valve, a rocker engageable with either valve to vary its normal action, a shaft driven by a moving part of the engine and having a cam thereon connected to the rocker, and means to shift the 95 cam to vary the operation of the rocker and valves.

2. In an explosive engine, the combination of a compression cylinder having inlet and outlet valves, a reservoir connected to the 100 outlet valve, a shaft driven by a moving part of the engine, a cam on the shaft, having an operative connection to the valves, the cam having at least three positions, in one of which the connection is idle and the 105 valves act normally, in another of which the inlet valve is held open during the in-stroke to avoid compression, and in a third of which the normal action of the valves is reversed.

In testimony whereof I have signed my name to this specification in the presence of 110 two subscribing witnesses.

FRANK J. MILLER.
